(57) **CLAIM**

I claim the ornamental design for [a] an articulating mount, as shown and described.

DESCRIPTION

FIG. 1 is a perspective view showing a first position of the articulating mount showing my new design;

FIG. 2 is a front view thereof;

FIG. 3 is a top plan view thereof;

FIG. 4 is a bottom view thereof;

FIG. 5 is a right side view thereof;

FIG. 6 is a left side view thereof;
FIG. 7 is a rear view thereof;
FIG. 8 is a perspective view showing a second position of the articulating mount of FIG. 1;
FIG. 9 is a front view of the articulating mount in FIG. 8;
FIG. 10 is a top plan view of the articulating mount in FIG. 8;
FIG. 11 is a bottom view of the articulating mount in FIG. 8;
FIG. 12 is a right view of the articulating mount in FIG. 8;
FIG. 13 is a left side view of the articulating mount in FIG. 8;
and
FIG. 14 is a rear view of the articulating mount in FIG. 8.
FIG. 15 is a perspective view showing a first position of another embodiment of the articulating mount showing my new design;
FIG. 16 is a front view of the articulating mount in FIG. 15;
FIG. 17 is a top plan view of the articulating mount in FIG. 15;
FIG. 18 is a bottom view of the articulating mount in FIG. 15;
FIG. 19 is a right side view of the articulating mount in FIG. 15;
FIG. 20 is a left side view of the articulating mount in FIG. 15;
and
FIG. 21 is a rear view of the articulating mount in FIG. 15.
FIG. 22 is a perspective view showing a second position of the articulating mount of FIG. 15;
FIG. 23 is a front view of the articulating mount in FIG. 22;
FIG. 24 is a top plan view of the articulating mount in FIG. 22;
FIG. 25 is a bottom view of the articulating mount in FIG. 22;
FIG. 26 is a right view of the articulating mount in FIG. 22;
FIG. 27 is a left side view of the articulating mount in FIG. 22;
and
FIG. 28 is a rear view of the articulating mount in FIG. 22.
FIG. 29 is a perspective view of an articulating mount showing my new design;
FIG. 30 is a rear elevational view thereof;
FIG. 31 is a top plan view thereof;
FIG. 32 is a bottom plan view thereof;
FIG. 33 is a right side view thereof;
FIG. 34 is a left side view thereof; and,
FIG. 35 is a front elevational view thereof.
The broken lines shown are for illustrative purposes only and form no part of the claimed design.

1 Claim, 16 Drawing Sheets

Matter enclosed in heavy brackets [ ] appears in the original patent but forms no part of this reissue; matter printed in italics indicates the additions made by reissue.
